ROCKING BED CONSTRUCTION

Samuel Y. Gibbon, Jenkintown, Pa., assignor to Air-Shields, Inc., Bucks County, Pa., a corporation of Delaware

Application June 2, 1953, Serial No. 359,108

2 Claims. (Cl. 128—28)

This invention relates to improvements in rocking beds such as are used for improving or assisting respiration.

Rocking bed apparatus in which a patient lies in a prone or semi-prone position and the bed oscillates about a transverse axis has been used in connection with patients who require assistance in their breathing action. A rocking-type bed alternately imposing the weight of the internal organs against the diaphragm and then removing this weight by means of the change in the inclination of the body serves to actuate the diaphragm in a manner which imposes collapsing and expansion action on the lungs. The period at which rocking motion occurs may be timed to provide a normal breathing interval. Blood circulation is also improved by this shifting of pressures.

The apparatus of the present invention incorporates a number of features which are applicable to rocking beds in general but are particularly valuable in connection with rocking beds constructed for use with infants. In addition to being useful in connection with various respiratory ailments the apparatus is particularly valuable for very young infants whose breathing functions have not developed to normal because of some malfunctioning of the respiratory system. It has been found that the apparatus is particularly effective for inducing initial breathing in infants who do not respond to the normal methods used to cause breathing to start. The rocking bed apparatus of the present invention has been used successfully in many instances to induce breathing action and to assist in maintaining it until normal respiration occurs.

One of the primary objects of the invention is the provision of rocking bed apparatus in which the transverse rocking pivot is located at the upper end of the bed close to the plane in which the patient lies. With the rocking axis in this location the lower portion of the patient's head lies close to the axis with the result that very little movement of the head occurs except a slight angular displacement. Thus administration of normal attention to the infant such as swabbing its mouth or aspirating its throat for the clearing of mucus and the like may be continued while the rocking motion is in process.

Another object of the invention is the provision of a frame structure which supports the complete bassinet unit in a simple fashion with a removable pivot to allow the bassinet to be quickly attached or removed from the rocking structure to allow compact storage of the apparatus for shipment or when it is not being used.

A further object of the invention is the provision of a rocking bed structure which is provided with a concentrated balance weight at the proper location to give a natural pendular frequency to the apparatus which is close to the normal operating period. This construction permits operation near these natural frequencies with a minimum expenditure of driving power.

A still further object of the invention is the provision of a pallet frame and cover on which the patient is supported which consists of a sheet of fabric attached to a frame in a fashion which allows rapid removal and re-

2

placement to give proper sanitary conditions. This construction further provides for a comfortable support which conforms to the shape of the body and may be constructed from materials which are safe for use in an atmosphere having mixtures of oxygen or ether.

Another object of the invention is the provision of an operating mechanism which permits not only adjustment of the speed of oscillation above and below the normal average, but also provides for adjusting the amplitude of oscillation within a suitable range thereby permitting adjustment to suit the severity of the requirements in different cases.

How the foregoing objects and advantages are attained will be clear from the following description of the drawings in which—

Figure 1 is a side elevational view of the rocking bed apparatus incorporating the features of the present invention.

Figure 2 is an end elevational view of the apparatus shown in Figure 1.

Figure 3 is a sectional view taken in the direction of arrows 3—3, Figure 1, showing the construction which provides for change in amplitude of oscillating motion.

Figure 4 is a plan view taken along the direction of arrows 4—4, Figure 2, showing additional details of the drive link mechanism.

Figure 5 is a fragmentary view in plan showing a corner of the pallet frame and cover construction.

In Figures 1 and 2 it will be seen that the lower cabinet 10 is provided with castoring wheels 11 which permit the unit to be moved about in any direction with a minimum of effort. Cabinet 10 houses the power and transmitting mechanism which produces the actuating forces for oscillating the bed unit. Supported on the cabinet 10 are side frame members 12 which extend above the cabinet at each side thereof to form a structural support for the bed unit. In the horizontal portion of frame member 12 at each side of the apparatus there is a section 13 near one end thereof which is preferably of square cross-section and provided with a vertical cylindrical opening 14, into which upright column 15 is fitted. At the upper end of each column 15 there is a cylindrical housing 16 which encloses the bearing used to support pivot shaft 17. Each shaft 17 is attached to a boss 18 supported on a movable side frame member 19.

Side frame members 19 extend downwardly and are connected to the lower frame member 20 which extends transversely to form a sort of cradle structure to support the rocking bed unit. A pair of spaced longitudinally extending angle stiffeners 21, 21 are provided on the bottom of the bassinet enclosure 22. These stiffeners rest on a pair of supporting plates 23, 23 which are secured to the side frame members 19, 19 by spacer blocks as clearly seen in Figure 2.

A transversely extending block or weight 24 is rigidly secured to the angle stiffeners 21, 21. This weight 24 concentrates a major portion of the weight of the apparatus in the end of the swinging mechanism which is closest to the pivot 17. In this way, the weight 24 acts to counterbalance in large part the weight of other parts of the apparatus on the other side of the pivot.

The bassinet is pivotally connected to the supporting plates 23, 23 by means of pivot pins 25, 25 extending into the weight 24. Thus the bassinet unit or bed member 22 is independently pivoted to the cradle structure by pivot 25 and may be swung upwardly away from it on the pivot. The normal position of the center of gravity of the weight of the bassinet and contents normally holds the unit in proper position in the cradle as shown. However in case an operator should inadvertently insert his arm or some other portion of his body between the side frame 12 and the bottom of the bassinet 22 when it

is in its upward position of swing, no damage can be done, inasmuch as the bassinet will swing about the pivot 25 and only its weight will be imposed upon the arm or object which may contact it. Thus damage to the operator or apparatus is avoided inasmuch as the forces from the drive mechanism are not transferred to the inserted object.

A pallet or occupant's support is placed in the bottom of the bassinet unit 22. This is constructed with a complete encircling frame 26 which is of rectangular shape to fit inside the compartment 22. A corner of the frame and pallet construction is illustrated in Figure 5. In order to support the frame 26 above the bottom surface of the bassinet enclosure 22 cross members 27 are provided with side vertical supports to engage the frame 26. Three of these supports 27 are shown, one at each end and one in the center of the frame. The supporting diaphragm 28 which is attached to the frame 26 may be made of any suitable fabric, preferably one which is electrically inert so that it is safe for use in explosive or highly inflammable atmosphere. In order to provide for quick attachment to or removal from the frame 26, the member 28 is provided with reinforced edges which are proportioned to pass around the frame 26 and fold back on itself to be fastened at intervals by means of snap fasteners 29. The corners of the diaphragm member 28 may be cut out as illustrated at 30, Figure 5. A flexible pallet of this nature deforms to engage the form of the body and serves to prevent shifting of the occupant under the angular movement.

The bassinet body 22 is provided with a lid or cover 31 so that the bassinet unit may be completely enclosed in cases where it is desired to isolate the occupant or in order to provide concentrations of oxygen or other therapeutic materials. Cover 31 is preferably made from materials which will not harbor a static charge which could be dangerous in an atmosphere which is composed of oxygen and ether mixtures or other explosive gases frequently found in hospital operating rooms and the like. In order to provide a satisfactory cover a frame 32 is provided, the lid being composed of two similar portions hinged at the center at 33. In this way either end of the lid may be raised independently for access to the patient or the complete lid may be removed or set in place quickly by means of projecting portions of the hinges 33 which engage in suitable slots in the sides of the enclosure 22, thereby providing for the locating of the lid in a simple and accurate manner. Glass 34 or other suitable transparent material may be inserted in frame 32 to permit easy observation of the patient in the enclosure.

If desired, auxiliary apparatus may be attached to the enclosure unit 22. An oxygen and humidifying system, as well as an aspirating system is shown connected to the enclosure 22. In Figures 1 and 2 it will be seen that large diameter pipe 35 extends from the end of the enclosure to a container 36. Associated with the pipe 35 is an atomizer unit to which oxygen under pressure may be fed. This in turn creates a reduced pressure system which draws and atomizes water from the container 36 so that it produces a fine mist which is transmitted with the oxygen into the enclosure 22. This portion of the apparatus operates in the same general manner as the humidifying apparatus shown in U. S. Patents 2,593,134 and 2,624,337, issued April 15, 1952, and January 6, 1953, respectively. The flow of oxygen through one channel of the atomizer produces a suction action in the other channel of the atomizer. This suction may be utilized to operate the aspirator unit by connecting it to this source of low pressure. Thus the pipe 37 which is connected with the suction leg of the atomizer produces reduced pressure in the container 38 and likewise in the tube 39. Thus by connecting a suction tube or catheter to the internal end of pipe 39 mucus and the like may be withdrawn from the patient while the bed is operating. This is easily accomplished since the mouth of the occu-

pant lies close to the pivotal axis and therefore little motion is involved at this point during the aspirating operation.

As will best be seen from Figure 1 the drive mechanism is housed in cabinet 10. Here it will be seen that electric motor 40 drives the gear reduction unit 41 through the medium of pulley 42, belt 43 and pulley 44. Suitable gearing is provided in reducer 41 so that crank member 45 is driven at reduced speed. One end of connecting rod 46 is attached to the crank member 45 by a pivot 47 and is attached to arm 48 by another pivot 49. Lower end of arm 48 is pivoted at 50a to a bracket 50 and thus is arranged for swinging movement under the influence of connecting rod 46. The upper end of vertical arm 48 is connected by means of connecting rod 51 to arm 52 which is rigidly attached to the swinging frame structure which carries the bed or bassinet unit.

The details of construction of the vertical arm and its connecting rod attachments will be more clearly seen in Figures 3 and 4. In order to provide for different amplitudes of rocking oscillation the connecting rod 46 is arranged to be moved with respect to the vertical arm 48 and thereby act at different distances from the fulcrum at the fitting 50. In order to permit change of the position of the pivot structure 49 a pair of brackets 53 and 54 are attached to the vertical arm 48 and in turn these brackets support a threaded rod 55 which extends upwardly and terminates in thumb screw 56. Attached to the pivot 49 is a female threaded cylindrical part 57. A slot 58 in the vertical arm 48 allows the pivot 49 to move relative to the arm 48 in a longitudinal or vertical direction. Proper positioning of the pivot member 49 in the slot is controlled by the washer 59 and flanged bearing member 60. Connecting rod 46 engages the bearing member 60 through which pivot member 49 passes. Thus by turning thumb screw 56 the position of the pivot 49 may be moved along the slot 58 thereby changing the amplitude of motion of the upper end of the arm 48.

The construction of the horizontal connecting rod 51 between the upper end of swinging arm 48 and the arm 52 is also shown in Figures 3 and 4 where it will be noted that connecting rod 51 is attached to the arm 52 by means of a pivot or bolt member 61 and to the upper end of arm 48 by means of a special pivot member 62. It will be observed that pivot member 62 is arranged to pass through one side of the connecting rod 51, then through the arm 48 into the other side of connecting rod 51. Connecting rod 51 is further constructed to permit the head of pivot 62 to be embedded in it so that the cover member 63 which is swingably attached to the connecting rod 51 by means of a small rivet 64 can be swung either out of position to permit removal of the pivot 62 or into position to retain 62 in place. Thus a quick disconnection is provided in which removal of pivot 62 permits the rocking bed and its complete supporting frame structure to be lifted from the lower unit by lifting out the vertical supports 15 from their sockets in the enlarged portion of members 12, thus removing the complete upper assembly. With the mechanism just described for varying the amplitude of oscillation of the bed movement, the rocking action may be changed from an amplitude as indicated by center lines 65, 65a to an increased amplitude of motion as indicated by lines 66, 66a.

To change the speed of oscillation, pulleys 42 and 44 are preferably of the variable diameter type in which the diameter of the driving pulley may be progressively increased while that of the driven pulley progressively decreases and vice versa.

Use of the apparatus is relatively simple and does not require a highly trained operator. The infant is placed in the bassinet unit on the pallet with its head at the end adjacent the rocking pivot as indicated by the dotted outline 67. By adjusting the thumb screw 56 the desired amplitude of oscillation of the bed is selected and the

pulleys 42 and 44 are adjusted to give the desired speed. A normal speed of 20 oscillations per minute with adjustments on either side from approximately 12 oscillations per minute to 30 oscillations per minute is preferably provided. With the lid in position the motor 40 may then be started and the equipment operated to produce resuscitation action. Oxygen and humidification may be supplied to the chamber as desired, and in case it is necessary to have direct access to the patient for such purposes as aspiration of mucus or the like, the upper portion of the lid may be folded back on its pivot.

From the foregoing it will be evident that I have provided an improved construction for rocking beds, particularly those for use with infants. By the construction illustrated the rocking action may take place about an axis close to the patient's head and thus avoids large amplitudes or rapid motion in the head region where such motion might have a detrimental physiological effect. The angular motion, however, produces the desired physical effect in displacing the weight of the internal organs so that full resuscitation action is applied to the diaphragm and improved blood circulation is induced by change in pressure direction. This location of the pivot has the further benefit of permitting administration of medicaments, using a swab or aspirator or giving similar attention to the occupant while the rocking bed is in action. By constructing the bassinet portion as a separate unit which may be attached to a rocking framework by pivotal means the danger of causing injury to the operator in the event that he is struck by the swinging unit is avoided. The provision of proper counterweight structure also provides not only for improved static balance of the apparatus but permits operation at, or near, the normal natural pendular frequency of operation with a minimum of power. The simple, manually operated screw adjusting mechanism, provides an improved method of changing the amplitude of rocking action.

I claim:

1. A rocking bed assembly for use with individuals requiring resuscitating action including a bed member for supporting the patient, a structural support on which said bed member is mounted, pivotal parts supporting said bed member on said support for providing a transverse rocking pivot, the axis of said pivot being located close to the end of the bed member where the head is normally located and at an elevation higher than the plane of the bed surface supporting the patient, actuating mechanism with a connection to said bed member for producing the rocking motion.
2. A rocking bed construction having a bed member and a supporting structure on which the bed member is mounted for rocking motion, a transverse pivot structure having bearing parts attached to move with the bed member and cooperating bearing parts attached to the supporting structure, the axis of said pivotal structure being located above the surface of the bed member in a position near the upper end of said bed member at a point approximating the location of the normal position of the occupant's mouth, power drive apparatus and connections between said apparatus and said bed member for causing the rocking action.
